(57) **CLAIM**

The ornamental designs for a set of zero through nine character dolls, as shown.

DESCRIPTION

FIG. 1 is a front view of a set of zero through nine character dolls;

FIG. 2 is a front view of a number zero (0) doll of the present invention showing the doll's proposed design and face;

FIG. 3 is a perspective view of a number zero (0) doll;

FIG. 4 is a front view of a number one (1) doll of the present invention showing the doll's design and face;

FIG. 5 is a perspective view of a number one (1) doll;

FIG. 6 is a front view of a number two (2) doll of the present invention showing the doll's design and face;

FIG. 7 is a perspective view of a number two (2) doll;

FIG. 8 is a front view of a number three (3) doll of the present invention showing the doll's design and face;

FIG. 9 is a perspective view of a number three (3) doll;

FIG. 10 is a front view of a number four (4) doll of the present invention showing the doll's design and face;

FIG. 11 is a perspective view of a number four (4) doll;

FIG. 12 is a front view of a number five (5) doll of the present invention showing the doll's design and face;

FIG. 13 is a perspective view of a number five (5) doll;

FIG. 14 is a front view of a number six (6) doll of the present invention showing the doll's design and face;

FIG. 15 is a perspective view of a number six (6) doll;

FIG. 16 is a front view of a number seven (7) doll of the present invention showing the doll's design and face;

FIG. 17 is a perspective view of a number seven (7) doll;

FIG. 18 is a front view of a number eight (8) doll of the present invention showing the doll's design and face;

FIG. 19 is a perspective view of a number eight (8) doll;

FIG. 20 is a front view of a number nine (9) doll of the present invention showing the doll's design and shape; and,

FIG. 21 is a perspective view of a number nine (9) doll.

Any broken line showings are for the purpose of illustrating environmental structure and form no part of the claimed design.
